ABSTRACT

A rotary switch comprising: a plurality of n different fixed contacts where n is an integer at least equal to 2, said contacts being disposed in spaced position along a circle and designated as the first, second . . . and n th contacts respectively; an electrically conductive wiper extending radially outward from the center of the circle and fixed in position at the center, the opposite end of the wiper making electrical connection with any fixed contact when the wiper is properly positioned; first means responsive to incoming pulses to cause said wiper to rotate through a selected arc each time a pulse is received whereby said wiper can be successively advanced to make electrical connection with each of the first, second . . . and n th contacts in turn and thereafter to repeat the sequence as required, said wiper when connected to said first contact being in the home position; a pair of normally closed contacts; and second means responsive to the rotation of the wiper to separate the contact in said pair when and only when the wiper is in home position.

ROTARY SWITCH

THE PRIOR ART

British Pat. No. 1,147,690 discloses an electromechanical rotary switch having a contact wiper in the form of a single flexible member fixed at one end and made to sweep in a rotary motion at the other. This wiper has a straight portion which rests normally on one of a number of contacts disposed in spaced positions along a circle centered on fixed point.

The switching motion is derived from two hollow cylinders disposed vertically and concentrically one within the other, each cylinder having a circular profile of saw tooth form on its upper edge. The outer cylinder is stationary and its profile does not move. The inner cylinder can be reciprocated back and forth along its axis whereby the inner profile moves toward and away from the wiper. The inner and outer profiles have teeth which are relatively displaced angularly by approximately half a pitch. The motion of the inner cylinder towards the wiper lifts the straight portion of the wiper laying radially across both profiles at a common point on their circumferences, over the tip of the tooth of the outer cylinder and so to slide down the face of the back of the tooth (which is sloping) to be brought to a halt by the near vertical face of the next tooth of the inner cylinder. The inner cylinder is then allowed to return to its former position, allowing the wiper to continue down the slope of the outer tooth and consequently over the tip of the inner tooth, the wiper coming to rest on the next contact face.

The wiper can thus be caused to step around the peripherally disposed fixed contacts in successive circles, each complete circle being a complete cycle. However, if one specified contact is designated as the zero or homing contact, it will be seen that the wiper, once having left the zero or home position, can only be return thereto after completion of a switching cycle.

For many applications, as for example in telephony, it is necessary to provide means in such a rotary switch which can override all other operations upon command and cause the wiper to be automatically returned in one continuous movement to home position. This known switch lacks such means.

SUMMARY OF THE INVENTION

My invention is directed toward a rotary switch of the type described above which is provided with automatic homing control. To this end, my rotary switch employs a plurality of n different fixed contact where n is an integer at least equal to 2, said contacts being disposed in spaced position along a circle and designated as the first, second . . . and n th contacts respectively. The switch also includes an elongated electrically conductive wiper extending radially outward from the center of the circle. The inner end of the wiper is fixed. Its outer end makes electrical connection with any fixed contact when the wiper is properly positioned.

First means responsive to incoming pulses causes the wiper to rotate through a selected arc each time a pulse is received whereby said wiper can be successively advanced to make electrical connection with each of the first, second . . . and n th contacts in turn and thereafter to repeat the sequence as required. The position of the wiper when connected to said first contact is designated in the home position.

In order to control the homing action, the switch is also provided with a pair of normally closed contacts. Second means responsive to the rotation of the wiper cause the contacts in said pair to separate when and only when the wiper is in home position. Third means when energized through the closed contacts of the pair cause the wiper to be automatically advanced in one continuous motion from any other position to the home position. The third means is automatically disabled when the contacts in said pair are separated.

BRIEF DESCRIPTION OF THE DRAWINGS

In the drawings:

FIG. 1 shows, in side elevation, one embodiment of my invention;

FIG. 2 is a top view thereof;

FIG. 3 is a cross section taken along line 3 — 3 in FIG. 2;

FIG. 4 is a view taken along line 4 — 4 in FIG. 3;

FIGS 5-9 are diagrammatic views illustrating various steps in the switching operation employed in my switch;

FIG. 10 is a view taken along line 10 — 10 in FIG. 3;

FIG. 11 is a view similar to FIG. 10 but showing the contacts in different positions;

FIG. 12 is a side view of a modification of the contacts arrangement shown in the preceding Figures;

FIG. 13 is a view similar to FIG. 12 but showing another modification; and

FIG. 14 is a view taken along line 14 — 14 in FIG. 13.

DETAILED DESCRIPTION OF PREFERRED EMBODIMENTS

Referring first to FIGS 1 — 11, my switch comprises a vertical cylindrical housing 10 closed at its ends by top plate 12 and base plate 14 which serve as caps. The casting 10 is provided with an inner annular shoulder 20 against which is seated a radial flange 22 of a hollow cylindrical insulating vertical member 4. Member 4 has a top horizontal edge with stationary saw teeth 24. A second hollow cylindrical insulated member 6 constrained to move vertically up and down is disposed concentrically within member 4. Member 6 has a top horizontal edge with saw teeth 26. The teeth in the two members 4 and 6 are offset by approximately half a pitch.

A plurality of electrical contacts 2 are disposed horizontally and extend inward through the housing to lie in equidistantly spaced positions along a circle centered around the axis of the housing.

An elongated electrically conductive wiper has a wiper portion 8 which overlies anyone of contacts 2 and is in electrical engagement therewith. Wiper portion 8 is at the end of an arm 16 which extends horizontally from a helical spring section 18 across the two saw teeth portions of members 4 and 6.

Section 18 extends inclinedly downward from an opening 28 in the center of plate 12. An electrically non-conductive support serves as a core 30 about which the spring is disposed. A vertical top portion 32 of the support carries a vertical cam surface 34. A pair of normally closed contacts 36 and 38 cooperate with the cam surface in a manner described below.

Member 6 is secured at its center to the top end of a non-magnetic bar 40 vertically disposed and aligned with the axis of the housing. The bottom end of the bar

is secured via bias spring 42 to the center of bottom plate 3 and is also secured to a magnetic piston 84. Guide means 44 restrains the bar so that it cannot move horizontally.

A relay type coil 46 has a vertical central bore in 5 which the bar 40 is disposed.

When the coil is energized by a pulse applied between the two end terminals, member 6 is raised and its saw teeth extend above the level of the saw teeth of member 4. As soon as the coil is deenergized, spring 42 10 will pull member 6 downward until its teeth are below the level of the teeth of member 4. This motion, because of the relative offset of the teeth of the two members, causes the arm 16 to describe an arc and wiper 8 to advance from engagement with one contact 15 2 to engagement with the next adjacent contact 2 each time coil 46 is pulsed by individual step pulses.

In order to perform the homing action, contacts 36 are connected in circuit with an on-off switch 50 and a generator 52 of a pulse train. This generator is also coupled to the coil 46. When switch 50 is open no homing action occurs. When switch 50 is closed, coil 46 is periodically and rapidly pulsed and the arm is stepped around until the arm reaches a position at which the wiper engages a selected one of contacts 2 designated 25 as a home contact and identifying home position. At this point contacts 36 and 38 separate breaking the circuit.

Contacts 36 and 38 cooperate with the cam surface 34. As the arm 16 moves, this surface rotates. The surface is so arranged that the contacts 36 and 38 separate only at the home position as shown in FIGS. 10 and 11.

In FIG. 12, blade contacts 60 and 62 are substituted for contacts 36 and 38. The function remains the same.

In FIGS. 13 and 14, commutator contacts 70 and 72 35 are substituted for contacts 36 and 38, and the cam surface is modified as shown at 74. The function still remains the same.

While I have described my invention with particular reference to the detailed embodiments, my protection 40 is to be limited only by the terms of the claims which follow.

I claim:

1. A rotary switch comprising
a first cylindrical member having stationary saw 45 teeth on one edge thereof;
a second cylindrical member including stationary saw teeth on one edge thereof and being slideably mounted in a longitudinal direction concentrically within said first cylindrical member, the saw-tooth 50

edge of said second cylindrical member being positioned lower than and offset from the saw-tooth edge of said first cylindrical member;
means responsive to a first signal source for causing longitudinal movement of the cylindrical members with respect to each other;
a plurality of n different contacts where n is an integer of at least two, said contacts being disposed concentric with one of said cylindrical members;
wiper means including a camming surface on one end thereof and being responsive to the axial movement of said second cylindrical member to advance the other end along said plurality of contacts; and
homing means, mechanically coupled to said camming surface and electrically coupled to means for causing longitudinal movement being operative in response to a second signal source to return said wiper means to a predetermined one of said plurality of n contacts from any other one of said plurality of n contacts.

2. A rotary switch according to claim 1 wherein said wiper means includes

a coil spring having one end substantially orthogonal to the concentric axis of said first and second cylindrical members and the other end substantially parallel thereto; and
a core member fixedly positioned within said coil spring and rotatably mounted with respect to the axis of said first and second cylindrical members, said core member having a concentrically increasing camming surface and having a transition between the high and low portions associated with the predetermined one of said plurality of n contacts.

3. A rotary switch according to claim 2 wherein said homing means includes

switching means including a pair of normally closed contacts, one contact of said pair being tangentially displaced along said camming surface from the other contact of said pair such that said one contact passes over the transition and drops to the lower portion of said camming surface to thereby open the normally closed contacts; and
connecting means coupled between the second source of signals and said means for causing and being adaptive to couple signals from said second source to said means for causing when said pair of contacts are in the normally closed condition.
